(57) **CLAIM**

We claim the ornamental design for an oral irrigator handle, as shown and described.

DESCRIPTION

FIG. 1 is a front isometric view of an oral irrigator handle with a tip shown in broken lines for environment.

FIG. 2 is a front elevation view of the oral irrigator handle of FIG. 1.

FIG. 3 is a rear elevation view of the oral irrigator handle of FIG. 2.

FIG. 4 is a right side elevation view of the oral irrigator handle of FIG. 2.

FIG. 5 is a left side elevation view of the oral irrigator handle of FIG. 2.

FIG. 6 is a top plan view of the oral irrigator handle of FIG. 2; and,

FIG. 7 is a bottom plan view of the oral irrigator handle of FIG. 2.

The broken line showing of the tip in FIG. 1 depicts environmental structure and forms no part of the claimed design. The dash-dash broken lines in the drawings depict portions of the oral irrigator handle that form no part of the claimed design. The dash-dot broken lines in the drawings define the bounds of the claimed design and form no part thereof.
